UNITED STATES PATENT OFFICE.

CHARLES ESCHENBRUECHER, OF PHILADELPHIA, PENNSYLVANIA.

COMBINATION TABLE AND BED.

981,402.

Specification of Letters Patent. Patented Jan. 10, 1911.

Application filed September 3, 1910. Serial No. 580,404.

To all whom it may concern:

Be it known that I, CHARLES ESCHENBRUECHER, a citizen of the United States, residing at Philadelphia, in the county of 5 Philadelphia and State of Pennsylvania, have invented certain new and useful Improvements in Combination Tables and Beds, of which the following is a specification.

10 My invention relates to improvements in combination tables and beds, an object of the invention being to provide a combination device of this character which may be readily unfolded and utilized as a bed, and which 15 when folded will have the ordinary appearance of a table giving no appearance whatever of a bed.

A further object is to provide a combination device of this character which will perform with equal efficiency both of its functions as a bed and table, and which will be neat and attractive in appearance, strong and durable in use, and easily operated to form the same into a table or a bed.

25 With these and other objects in view, the invention consists in certain novel features of construction and combinations and arrangements of parts, as will be more fully hereinafter described and pointed out in the 30 claims.

In the accompanying drawings: Figure 1, is a perspective view illustrating the device in its table form. Fig. 2, is a similar view showing the device open in its bed form. 35 Fig. 3, is a view in longitudinal section of Fig. 2. Fig. 4, is a plan view of Fig. 2. Figs. 5, and 6, are enlarged fragmentary views in vertical and horizontal section illustrating the manner of securing one of the 40 adjustable legs. Fig. 7, is a view in cross section of Fig. 1. Fig. 8, is a view in longitudinal section of Fig. 1. Fig. 9, is a perspective view of the combined spring and mattress, and Fig. 10, is a detail perspective 45 view of one of the adjustable legs.

In constructing my improvements, I employ preferably four fixed legs 1, which are secured to a shelf 2, and are connected at their upper ends by bars 3, three of these 50 bars 3 being employed as shown most clearly in Fig. 2. A box 4 constituting the top of the table is connected by hinges 5 with the bars 3, and in two of the corner blocks 6 of the box, adjustable legs 7 are mounted. These

legs 7 are adapted, when the box is in an 55 inverted position to form the table top, to project through the bars 3 into longitudinal recesses 8 in fixed legs 1, and are secured in said legs by means of rods 9 which are adapted to engage in any of a series of 60 notches 10 in the legs 7, and securely lock the box on the fixed legs 1. The blocks 6 are also provided with spring pressed rods 11, so as to lock the adjustable legs in the position shown in Fig. 2, to support the box in 65 its open position as shown. In Fig. 1, it will be noted that there appear four of these adjustable legs 7, as a matter of fact two of these legs are mere blinds so as to give a uniform appearance to the table, and the 70 legs are provided with rings 12 to facilitate their movement.

The rods 9 and 11 are mounted alike, that is, they are supported in brackets 13 and have coiled springs 14 thereon secured at 75 their respective ends to the bracket and to the rod. The bottom 15, and one side 16 of the box 4, are made separate from the other portions of the box, and are connected by hinges 17, so that when the box is swung to 80 the position shown in Fig. 2, these parts 15 and 16 will be supported upon the shelf 2, and at one edge of the part 15 an ornamental railing 18 corresponding to the railings 19 at the ends of the shelf.

85 20, represents a sectional or folding combined spring and mattress which is adapted to fit the bed shown in Fig. 2, when open, and also adapted to be folded so as to fit within the box as shown in Figs. 7 and 8. 90 When the mattress is in the box, the bottom 15 and one side 16 of the box are folded up and are suitably locked to the box by means of catches 21, when the box may be swung over on its hinges 5 onto the bar 3. The adjustable legs 7 are then locked in the fixed legs 1, and the table is complete, strong and steady. In order that a smooth surface may be provided for the bed when the bottom 15 and the side 16 are down, a thickness of material 22 is secured to the under face of the table top, and to this material 22 side 16 is hinged, this material 22, side 16, and bottom 15 being of the same thickness.

100 105 Various slight changes might be made in the general form and arrangement of parts described without departing from my invention, and hence I do not limit myself to the

precise details set forth, but consider myself at liberty to make such changes and alterations as fairly fall within the spirit and scope of the appended claims.

5 Having thus described my invention, what I claim as new and desire to secure by Letters Patent is:

1. A device of the character described comprising fixed legs, bars connecting the legs, 10 and a shelf connecting the legs, of a box forming a table top, the bottom and one side of said box hinged together, and to the top of the box, whereby they may be folded down on the shelf when the top is in inverted 15 position, hinges connecting said box with said bars, whereby said box may be folded down in a plane substantially the same as the shelf, and means supporting said box in said plane, substantially as described.

20 2. A device of the character described comprising fixed legs, bars connecting the legs, and a shelf connecting the legs, of a box forming a table top, hinges connecting said box with said bars, whereby said box may be 25 folded down in a plane substantially the same as the shelf, the bottom and one side of said box connected by hinges and connected by hinges with the box, whereby said bottom and said side may be folded down on the 30 shelf, and means for supporting said box in said plane, substantially as described.

3. A device of the character described comprising fixed legs, bars connecting the legs, and a shelf connecting the legs, of a box 35 forming a table top, the bottom and one side of said box hinged together, and to the top of the box, whereby they may be folded down on the shelf when the top is in inverted position, hinges connecting said box with 40 said bars, whereby said box may be folded down in a plane substantially the same as the shelf, adjustable legs in the corners of said box, and means for locking said legs at various adjustment in the corners, whereby 45 said legs may operate to support the box in its open position or be confined within the corners of the box, substantially as described.

4. A device of the character described comprising fixed legs, bars connecting the 50 legs, and a shelf connecting the legs, of a box forming a table top, hinges connecting said box with said bars, whereby said box may be folded down in a plane substantially the same as the shelf, the bottom and one side of 55 said box connected by hinges and connected by hinges with the box, whereby said bottom and said side may be folded down on the shelf, adjustable legs in the corners of said box, and means for locking said legs at various 60 adjustment in the corners, whereby said legs may operate to support the box in its open position or be confined within the corners of the box, substantially as described.

5. A device of the character described 65 comprising fixed legs, bars connecting the

legs, and a shelf connecting the legs, of a box forming a table top, the bottom and one side of said box hinged together, and to the top of the box, whereby they may be folded down on the shelf when the top is in inverted 70 position, hinges connecting said box with said bars, whereby said box may be folded down in a plane substantially the same as the shelf, adjustable legs in the corners of said box, means for locking said legs 75 at various adjustment in the corners, whereby said legs may operate to support the box in its open position or be confined within the corners of the box, said fixed legs having recesses therein for the reception of said 80 adjustable legs, said adjustable legs having a longitudinal series of notches therein, and catches engaging in the notches in said adjustable legs, whereby said adjustable legs are locked in the fixed legs, substantially as 85 described.

6. A device of the character described comprising fixed legs, bars connecting the legs, and a shelf connecting the legs, of a box forming a table top, hinges connecting 90 said box with said bars, whereby said box may be folded down in a plane substantially the same as the shelf, adjustable legs in the corners of said box, means for locking said legs at various adjustment in the corners, 95 whereby said legs may operate to support the box in its open position or be confined within the corners of the box, said fixed legs having recesses therein for the reception of said adjustable legs, said adjustable legs 100 having a longitudinal series of notches therein, catches engaging in the notches in said adjustable legs, whereby said adjustable legs are locked in the fixed legs, a combined spring and mattress adapted to be 105 folded and confined in the box, and said mattress adapted when opened to fit within the dimensions of the combined box and shelf, substantially as described.

7. A device of the character described 110 comprising fixed legs, bars connecting the legs, and a shelf connecting the legs, of a box forming a table top, hinges connecting said box with said bars, whereby said box may be folded down in a plane substantially 115 the same as the shelf, the bottom and one side of said box connected by hinges and connected by hinges with the box, whereby said bottom and said side may be folded down on the shelf, adjustable legs in the corners of 120 said box, and means for locking said legs at various adjustment in the corners, whereby said legs may operate to support the box in its open position or be confined within the corners of the box, said fixed legs having 125 recesses therein for the reception of said adjustable legs, said adjustable legs having a longitudinal series of notches therein, catches engaging in the notches in said adjustable legs, whereby said adjustable legs 130

are locked in the fixed legs, a combined
spring and mattress adapted to be folded
and confined in the box, and said mattress
adapted when opened to fit within the di-
5 mensions of the combined box and shelf,
substantially as described.

In testimony whereof I have signed my

name to this specification in the presence of
two subscribing witnesses.

CHARLES ESCHENBRUECHER.
